UNITED STATES PATENT OFFICE

VALORUS S. HOLLINGSWORTH, OF LOS ANGELES, CALIFORNIA, ASSIGNOR OF ONE-HALF
TO IRA M. HOLLINGSWORTH, OF LOS ANGELES, CALIFORNIA

WINDMILL

Application filed June 20, 1928. Serial No. 286,838.

This invention relates to windmills and has for an object the provision of an improved type of power take-off from a shaft rotated by a wind driven wheel.

Another object is the provision of a windmill wherein the power take-off from the shaft upon which the wheel is mounted is composed of a geared connection. Accordingly when the wheel shaft is rotated to exert a torque upon the take-up shaft a counter-torque is exerted against the wheel shaft which tends to rotate the wheel shaft about an axis through the center of the take-off shaft, resulting in removing the wheel from that position in which the wheel is enabled to transform the maximum amount of energy of the wind into mechanical energy. Another feature of my invention, therefore, is the provision of means for locking the wheel shaft against any movement other than rotation about its own longitudinal axis.

Another object is the provision of locking means as above described which are adapted to be released by the rudder vane of the windmill when the vane is forced out of alignment with the wheel shaft as a result of shifting of the wind and which is adapted to be automatically reset when the rudder vane again brings the fan into position of maximum efficiency.

A still further object is the provision of a windmill comprising a wheel mounted upon a horizontal shaft which is connected by gearing to a vertical shaft from which the power taken from the wind may be delivered to perform any useful work and in which the horizontal shaft is provided with a clutch by means of which the two shafts optionally may be connected or disconnected to permit the wheel to transmit its power to the vertical shaft or to permit the wheel to idle.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description as I may

adopt variations of the preferred form within the scope of my invention as set forth in the claims.

Referring to the drawings:

Figure 1 is a side elevation of a windmill 55 and the upper portion of its supporting tower showing the improved structure embodying my invention in actual operation;

Fig. 2 is a top plan view slightly enlarged, portions of the wheel and rudder vane being 60 broken away to reduce the length of the figure;

Fig. 3 is a vertical medial sectional view of the structure shown in Fig. 2;

Fig. 4 is a horizontal sectional view taken 65 upon the line 4-4 of Fig. 3 with the direction of view indicated by the arrows.

In terms of broad inclusion the device of the present invention comprises means for locking against rotary movement the frame 70 upon which the wheel shaft of a windmill is journaled, these locking means being adapted to be released by the rudder vane of the windmill when the wind or other air current driving the vane veers. Accordingly the 75 device finds a particular field of utility in permitting the power take-off from the windmill to be connected to the wheel shaft by gearing since the locking device prevents the countertorque of the power take-off from 80 turning the wheel out of the wind. Another feature of my invention is the provision of a clutch adapted to automatically disengage the cam shaft from the take-off shaft to permit the wheel to idle.

Specifically describing the invention in its preferred embodiment, the figures disclose a frame 6 mounted for revolution about a vertical axis upon a suitable supporting structure such as a tower 7. A vertically disposed 85 sleeve 8 is rigidly attached to the top of the tower, within which another sleeve 9 is journaled, this latter sleeve being preferably integral with the frame 6. Journals 11 and 12 at the front and back respectively of the 90 frame 6 provide means for mounting a horizontal wheel shaft 13, on the forward end of which a plurality of vanes 14 are mounted to form the wind wheel 16, it being understood that the configuration of the vanes 14 100

is such that when the wheel 16 is headed into the wind, that is, placed in such a position that the direction of the wind or other air current is substantially parallel to the wheel 5 shaft 13, the wheel 16 will be rotated, transforming energy from the air current into mechanical energy by rotating the shaft 13.

A power take-off shaft 17 extends vertically downwards through the sleeve 9 and is 10 revoluble therein. A bushing 18 may be provided between the shaft 17 and sleeve 9 to form a better bearing surface. A beveled gear 19 is carried by the shaft 17 adjacent its upper end preferably immediately below the 15 wheel shaft 13. This gear 19 is enmeshed with a driving gear 21 which is mounted for rotation upon the wheel shaft 13.

A sleeve 22 is mounted for longitudinal sliding movement upon the shaft 13 but is 20 prevented from rotary movement in respect thereto by a pin 23 rigid with the shaft 13 and extending through longitudinally extending slots 24 in the sleeve 22. A cone 26 is rigidly connected to the sleeve 22 and has a friction 25 lining 27 thereupon adapted to seat within the tapered bore 28 provided in a flange 29 which is rigidly connected to the gear 21. Thus it may be seen that a clutch is provided by means of which the power take-off shaft 17 30 optionally may be connected to the wheel shaft 13 to be rotated thereby or disconnected therefrom to permit idling of the wheel shaft 13 without consequent rotation of the take-off shaft 17. A spring 31 under compression between 35 the journal 12 and the sleeve 22 normally retains the clutch engaged.

A flange 36 formed on the after end of the sleeve 22 provides a shoulder 37 against which a finger 38 projecting from a plate 39, 40 is held by a spring 41 under tension between the finger 38 and a portion 42 of the frame 6. The plate 39 is slidable longitudinally upon the frame 6, being held in sliding engagement therewith by a screw 43 which extends 45 through a slot 44 in the plate 39 adjacent its forward end, to be threaded into the frame 6. The after end of the plate 39 is guided by extending through an aperture 46 in the portion 42 of the frame 6. The spring 31 is 50 heavier than the spring 41, with the result that the clutch is normally held engaged and the plate 39 is normally retained at the forward extreme of its movement. Consequ- 55 ently, the only function of the lighter spring 31, is to take up any lost motion which may develop between the clutch and the plate 39.

A rudder vane 51 is pivotally attached to the after end of the frame. For this purpose the portion 42 of the frame 6 is bent forward 60 as at 52; and the upper arm 53 with which the rudder vane 51 is provided, has a pivot pin 54 seated in the forward extending portion 52 of the frame 6. The lower arm 56 has another pin 57 extending upwards to seat 65 within the frame 6 in alignment with the pin

54, permitting the rudder 51 to swing about a vertical axis in respect to the frame 6.

A cam 61 is pivoted to the sliding plate 39 with a screw 62 or its equivalent, the point of attachment being aft of the portion 42 and the contour of the cam 61 being such that when the arm 63, with which the cam 61 is provided, extends straight back from the frame 6 the plate 39 is slid to the forward limit of its movement. The cam 61 is provided, however, with a shoulder 64 upon each side so that when the arm 63 is swung out of alignment with the frame 6 one of the shoulders 64 engages the portion 42 of the frame 6 and pulls the sliding plate 39 rearwards against the action of the spring 31, causing the finger 38 to slide the sleeve 22 and disengage the clutch.

The arm 63 is bifurcated at its outer end 66 for the sliding reception of the lower arm 56 of the rudder vane 51. As a result when the rudder vane 51 is swung out of alignment with the shaft 13, the cam 61 is swung to such position that one of its shoulders 64 engages the frame 6 and pulls the plate 39 rearwards, releasing the clutch.

Accordingly an arm 67 extends transversely from the rudder vane 51; and a cord 68 or other flexible member is attached to the outer end of the arm 67 and passes over the sheave 69 of a pulley to extend to a point adjacent the bottom of the tower 7 so that by pulling upon the lower end of the cord 68 the rudder vane may be swung to one side, causing the wheel 16 to be swung out of the wind and causing 100 the disengagement of the clutch.

A gear 71 or its equivalent is attached rigidly to the top of the tower 7; and another finger 72 extends rigidly from the sliding plate 39 through a slot 73 in the frame 6 and is engageable between any two of the teeth of the gear 71. The parts are so proportioned and arranged that when the sliding plate 39 is at the forward extreme with its movement the finger 72 is in engagement with the gear 71, and when the sliding plate 39 has been withdrawn to the after extreme of its movement the finger 72 is disengaged from the gear 71.

Hence, when the rudder vane 51 is in alignment with the shaft 13, or in other words, when the rudder vane 51 is in position to hold the wheel 16 in that position in which the wheel may convert the maximum amount of energy of the wind into mechanical energy, the frame 6 is locked against rotary movement, resulting in the wheel being held against moving out of its position of maximum efficiency. Thus the tendency of the counter torque from the take-off shaft 17 to rotate the frame 6 and the wheel 16 away from its position of maximum efficiency is overcome. However, when the wind veers, the rudder vane 51 will be swung to one side, resulting in the sliding of the plate 39 rearwards as described above. Thus the fin- 120

ger 72 is similarly withdrawn, disengaging the stationary gear 71 and releasing the frame 6 for free rotary movement. Because of the fact that that portion of the cam having the shortest radius is disposed against the portion 42 of the frame 6 when that shortest radius is in alignment with the shaft 13, the tendency of the spring 31 to slide the plate 39 forward, will result in pressing a shoulder eccentrically against the frame with such force that the frame will be turned to again head the wheel into the wind.

Since disengagement of the clutch is effected simultaneously with disengagement of the finger 72 from the gear 71, the connection between the wheel shaft and the take-off shaft is broken during the time that the rudder vane is again heading the wheel 16 into the wind. If this were not the case, more resistance to the action of the rudder vane would be offered, since the rotation of the gear 21 about the gear 19 which occurs when the frame 6 is turned and the take-off shaft held stationary, would cause rotation of either one or the other of the shafts during such movement of the frame 6.

I claim:

1. In a windmill a frame mounted upon a supporting structure for rotary movement in respect thereto about a vertical axis, a shaft journaled horizontally in said frame, a wheel carried by said shaft and adapted to be rotated by an air current when said shaft is substantially in parallelism with the direction of said current power transmitting means releasably connected to said shaft, a vertically disposed rudder carried by said frame whereby the frame is moved by the force of the air current to bring the shaft into parallelism with the direction of the current, a detent carried by said frame and adapted to releasably lock the frame to said supporting structure, and means operable by said rudder for withdrawing said detent from engaging position, and means operable by said rudder for releasing said power transmitting means.

2. In a windmill a frame mounted upon a supporting structure for rotary movement about a vertical axis, a shaft journaled horizontally in said frame, a wheel carried by said shaft and adapted to be rotated by an air current when said shaft is substantially in parallelism with the direction of said current, a driven member, releasable means for transmitting power from said shaft to said driven member, a vertically disposed rudder pivoted to said frame whereby the frame is moved by the force of said current to bring the shaft into parallelism with the direction of the current, a detent carried by said frame and adapted to releasably lock the frame to said supporting structure, an arm pivoted to said frame and extending therefrom to engage the rudder, a cam operably connected to said arm and operatively connected to said detent to

move the detent from engaging position when the rudder swings from alignment with said shaft, and means for automatically releasing said power transmitting means as the detent is moved from engaging position.

3. In a windmill a frame mounted for rotary movement about a vertical axis, a shaft journaled horizontally in said frame, a driving gear revolvably mounted upon said shaft, a clutch associated therewith optionally to lock the gear to the shaft to rotate therewith or to release the gear to rotate thereupon, a second shaft extending from said horizontal shaft, a driving gear affixed to said second shaft and enmeshed with said driving gear, a wheel affixed to said horizontal shaft, means operable by an air current for heading the wheel into said current and means operable by said heading means for disengaging the clutch.

4. In a windmill a frame mounted for rotary movement about a vertical axis, a shaft journaled horizontally in said frame, a driving gear revolvably mounted upon said shaft, a clutch associated therewith optionally to lock the gear to the shaft to rotate therewith or to release the gear to rotate thereupon, a second shaft extending from said horizontal shaft, a driving gear affixed to said second shaft and enmeshed with said driving gear, a wheel affixed to said horizontal shaft, a vertically disposed rudder pivoted to the frame and adapted to swing said wheel into that position in which it may receive the maximum impulse from an air current, and means operable by said rudder for disengaging the clutch when the rudder is swung from that position in which it heads the wheel into the air current.

5. In a windmill a frame mounted for rotary movement about a vertical axis, a shaft journaled horizontally in said frame, a driving gear revolvably mounted upon said shaft, a clutch associated therewith optionally to lock the gear to the shaft to rotate therewith or to release the gear to rotate thereupon, a second shaft extending from said horizontal shaft, a driving gear affixed to said second shaft and enmeshed with said driving gear, a wheel affixed to said horizontal shaft, a vertically disposed rudder pivoted to the frame and adapted to swing said wheel into that position in which it may receive the maximum impulse from an air current, a pivotally mounted arm engaged with said rudder and a cam associated therewith, said cam being operatively connected to said clutch to disengage the clutch when the rudder swings the arm to either side.

6. In a windmill a frame mounted upon a stationary support for rotary movement about a vertical axis, a shaft journaled horizontally in said frame, a driving gear revolvably mounted upon said shaft, a clutch associated therewith optionally to lock the gear

- to the shaft to rotate therewith or to release the gear to rotate thereupon, a second shaft extending from said horizontal shaft, a driving gear affixed to said second shaft and enmeshed with said driving gear, a wheel affixed to said horizontal shaft to rotate the horizontal shaft when driven by an air current, and remote control means for disengaging said clutch.
- 10 7. In a windmill a frame mounted upon a stationary support for rotary movement about a vertical axis, a shaft journaled horizontally in said frame, a driving gear revolubly mounted upon said shaft, a clutch associated therewith optionally to lock the gear to the shaft to rotate therewith or to release the gear to rotate thereupon, a second shaft extending from said horizontal shaft, a driving gear affixed to said second shaft and enmeshed with said driving gear, a wheel affixed to said horizontal shaft to rotate the horizontal shaft when driven by an air current, a vertically disposed rudder pivoted to the frame and adapted to swing said wheel into that position in which it may receive the maximum impulse from the air current, means operable by said rudder for disengaging the clutch when the rudder is swung from that position in which it heads the wheel into the air current, and remote control means for swinging said rudder to disengage the clutch.
- 15 8. In a windmill a frame mounted upon a stationary support for rotary movement about a vertical axis, a shaft journaled horizontally in said frame, a driving gear revolubly mounted upon said shaft, a clutch associated therewith optionally to lock the gear to the shaft to rotate therewith or to release the gear to rotate thereupon, a second shaft extending from said horizontal shaft, a driving gear affixed to said second shaft and enmeshed with said driving gear, a wheel affixed to said horizontal shaft to rotate the horizontal shaft when driven by an air current, a vertically disposed rudder pivoted to the frame and adapted to swing said wheel into that position in which it may receive the maximum impulse from the air current, means operable by said rudder for disengaging the clutch when the rudder is swung from that position in which it heads the wheel into the air current, a detent carried by said frame and adapted to releasably lock the frame to the stationary structure, and means operably connected to the rudder and operatively connected to the detent to move the detent to releasing position when the rudder is swung to disengage the clutch.
- 20 9. In testimony whereof I have signed my name to this specification.
- 25 VALORUS S. HOLLINGSWORTH.
